PAIR OF SPECTACLES

Joseph Gaspari, Rye, N. Y.

Application March 24, 1953, Serial No. 24,182

Term of patent 14 years

(Cl. D57—1)

To all whom it may concern:

Be it known that I, Joseph Gaspari, a citizen of the United States, residing in Rye, in the county of Westchester and State of New York, have invented a new, original, and ornamental Design for a Pair of Spectacles, of which the following is a specification, reference being had to the accompanying drawing, forming a part thereof.

In the drawing:

Fig. 1 is a front elevational view of a pair of spectacles, showing my new design.

Fig. 2 is a top plan view thereof, and

Fig. 3 is a side elevational view thereof.

I claim:

The ornamental design for a pair of spectacles, as shown.

JOSEPH GASPARI.
